UNITED STATES PATENT OFFICE.

ROY R. RITCHIEY, OF WICKENBURG, ARIZONA.

WATER-COOLING REFRIGERATOR.

1,077,557.

Specification of Letters Patent.

Patented Nov. 4, 1913.

Application filed December 18, 1912. Serial No. 737,527.

To all whom it may concern:

Be it known that I, Roy R. RITCHIEY, a citizen of the United States, residing at Wickenburg, in the county of Maricopa and State of Arizona, have invented certain new and useful Improvements in Water-Cooling Refrigerators, of which the following is a specification.

This invention relates to certain new and useful improvements in refrigerators and has for its primary object the provision of a refrigerator in which the ice is supported upon a water tank, whereby the contents of the same may be cooled.

15 The invention also aims to provide a refrigerator so designed as to allow for a free circulation of air through the ice and food chambers.

Another and more specific object of the invention resides in the provision of a novel form of drip trough removably secured upon the under side of the water tank.

20 The invention also aims to generally improve household refrigerators and to render them more economical, efficient and commercially desirable.

25 With these and other objects in view, as will become more apparent as the description proceeds, the invention consists in certain novel features of construction, combination and arrangement of parts as will be hereinafter fully described and claimed.

30 For a complete understanding of my invention, reference is to be had to the following description and accompanying drawings, in which,

Figure 1 is a front elevation of my improved refrigerator, the door being open and the front wall partly broken away; Fig. 40 2 is a horizontal sectional view taken on the plane of line 2—2 of Fig. 1; Fig. 3 is a transverse vertical sectional view, partly in elevation; and Fig. 4 is a horizontal sectional view through the water tank.

45 In the following description and accompanying drawings, similar parts will be referred to and designated by like reference characters.

50 Referring in detail to the drawings by numerals, 1 designates generally a refrigerator body or casing having the rear wall 2, bottom 3, end walls 4 and front wall 5. The lower portion of the front wall 5 has been cut away and the opening formed thereby is 55 closed by the door 6. A hinged cover 7 is

positioned upon the top of the refrigerator body and is adapted to close the same. The body of the refrigerator is provided with a metallic lining 8 and a suitable packing 9 is interposed between said lining and the walls 60 of the refrigerator.

The interior of the refrigerator 1 is rectangular in cross section and divided into two compartments by means of the vertical partition plate 10 which terminates in 65 spaced relationship to the bottom and top of the refrigerator. A water tank formed of sheet metal and having its side walls 11 soldered or otherwise secured to the end walls 12, is removably secured within one 70 of the compartments formed by the partition 10, by means of suitable brackets 13.

The top 14 of the water tank is centrally apertured as shown at 15 and provided around its periphery with the upwardly projecting flange 16 which is soldered or otherwise secured to the walls of the tank adjacent to the upper edges thereof. It will 75

be noted that this construction disposes the top 14 of the tank slightly below the top 80 edges thereof so that a block of ice 17 may be retained thereon. A duct or flue 18 having the laterally projecting flanges 19, is secured to the top 14 about the opening formed therein, projects downwardly 85

through the bottom of the water tank, and is secured to the depending flanges 20. Wires 21 are positioned across the flue 18 to prevent small particles of ice falling 90 through the same. Since the walls of the tank are spaced from the walls of the refrigerator, a free circulation of air is permitted.

Water is supplied to the tank by means of the pipe 22 having the funnel 23 formed on its upper end. A standard 24, connected to the funnel 23, and a band 25 slidably mounted upon said standard serve 95

to support an inverted water bottle in such position as to have its contents drain into the funnel. Water may be withdrawn from the tank by means of the faucet 26 connected to the pipe 27, which latter communicates with the interior of the water tank.

100 In order to provide for proper drainage of the melted ice, I provide the sheet metal trough 28 having rearwardly, downwardly and inwardly inclined bottom walls 28', and side walls 29 extended above the front and rear walls 30 and formed with the outwardly projecting flanges 31. Angular guide 110

or supporting plates 32 are secured in spaced relationship upon the bottom of the water tank and slidably support the trough 28 through the medium of the flanges 31. A handle 33 secured to the front wall of the trough provides a means whereby said trough may be easily removed from the refrigerator to permit cleaning. The trough is positioned under the duct 18, receives the ice water coming from the melted ice, and directs the same into the vertical drain pipe 34.

The space under the water tank may be used as a food compartment and I therefore provide the same with a shelf 35. The compartment 36 is also designed to be used for the reception of food and is therefore provided with the shelves 37.

It will be seen from the foregoing description, in connection with the accompanying drawings, that my refrigerator permits a free circulation of air about the ice, downwardly past the water tank, the food chamber arranged under the water tank, thence under the partition 10, upwardly through the food chamber 36 and over the top of the partition 10 into the ice chamber. The trough 28 is disposed in an out-of-the-way position, may be easily removed to permit cleaning and is admirably adapted for the purpose intended.

It is to be understood that while I have shown and described the preferred embodiment of my invention, I do not wish to be limited to this exact construction and arrangement of parts but may make such

changes as shall fall within the scope and spirit of the invention.

Having thus described by invention what I claim is:—

A refrigerator comprising a body, a water tank mounted within said body, the upper wall of said tank having an opening centrally arranged therein, disposed in a plane below the upper edges of the side walls of said tank and forming an ice support, upwardly extending flanges engaging the side walls of said tank and secured thereto, formed on the edges of said upper wall, wires disposed over the opening in said upper wall to prevent small particles of ice from falling therethrough, a duct extending entirely through said water tank, an annular outwardly extending flange formed on the upper end of said duct secured to the under surface of said upper wall adjacent the opening therein, a downwardly extending annular flange formed on the bottom of said tank and engaging the lower terminal of said duct, brackets formed on the under side of the bottom of said tank, a drip pan having outwardly extending flanges formed on its side walls, said flanges slidably engaging the brackets on the bottom of said tank, and said drip pan adapted to be removed from the refrigerator.

In testimony whereof I affix my signature in presence of two witnesses.

ROY R. RITCHHEY.
